US00D882622S

(12) **United States Design Patent** (10) Patent No.: **US D882,622 S**
Farnan et al. (45) Date of Patent: **** Apr. 28, 2020**

- (54) **DISPLAY SCREEN OR PORTION THEREOF WITH GRAPHICAL USER INTERFACE**
- (71) Applicant: **Tandem Diabetes Care, Inc.**, San Diego, CA (US)
- (72) Inventors: **Jason Farnan**, San Diego, CA (US); **Shaun Buchanan**, San Diego, CA (US); **Zion Greenlee**, San Diego, CA (US)
- (73) Assignee: **Tandem Diabetes Care, Inc.**, San Diego, CA (US)
- (**) Term: **15 Years**
- (21) Appl. No.: **29/660,721**
- (22) Filed: **Aug. 22, 2018**
- (51) LOC (12) Cl. **14-04**
- (52) U.S. Cl. **USPC D14/487; D14/488**
- (58) **Field of Classification Search**

Primary Examiner — Jack Reickel*Assistant Examiner* — John M Otte(74) *Attorney, Agent, or Firm* — Patterson Thuente
 Pedersen, P.A.**CLAIM**

We claim the ornamental design for a display screen or portion thereof with graphical user interface, as shown and described.

DESCRIPTION

The FIGURE is a front view of a display screen or portion thereof with graphical user interface showing our new design.

Items shown in broken lines are included for the purpose of illustrating environmental subject matter and portions of the article and form no part of the claimed invention.
